UNITED STATES PATENT OFFICE.

PAUL F. ELLMER AND CHARLES STREFF, OF PHILADELPHIA, PENNSYLVANIA.

HINGE CONSTRUCTION.

Application filed January 15, 1923. Serial No. 612,670.

To all whom it may concern:

Be it known that we, PAUL F. ELLMER and CHARLES STREFF, citizens of the United States, residing at Philadelphia, county of 5 Philadelphia, and State of Pennsylvania, have invented certain new and useful Improvements in Hinge Constructions, of which the following is a specification.

Our invention relates to hinge construction for use in connection with cellar doors, 10 hatches, trap doors and the like and has for its object to provide a hinge construction which may be supported by the wall of the opening and in such manner that the hinges 15 will be within the opening or hatchway when the door or hatch is closed so that there will be no projecting parts on the outside.

This object, and other advantageous ends 20 which will be described hereinafter, we attain in the following manner, reference being had to the accompanying drawings in which—

Figure 1 is a plan view of cellar doors 25 and a support having our invention applied thereto,

Figure 2 a section on line 2—2 of Figure 1,
Figure 3 a section on line 3—3 of Figure 2,

Figures 4, 5 and 6 are detail perspective 30 views of certain parts of our invention,

Figure 7 a view similar to Figure 2 illustrating the door in an open position, and

Figure 8 a front view of Figure 7 looking 35 in the direction of the arrow x.

The description of the hinge construction 40 will be as it is applied to a cellar door and the word door will be the generic term used for trap doors, hatches and the like.

Referring to the drawings, a support 1 made of angle iron has one of its legs 45 forming a wall 2 of the cellar opening and the other leg forming a cellar door support 3. A bracket 4 is secured to wall 2 and has an arm 5 pivoted thereto at 6. A bell crank lever 7 is pivoted to arm 5 at 8 and has one end 9 pivotally connected with bracket 4 by a link 10 and the other end 11 pivoted to a bracket 12 secured to a cellar door 13. The end of arm 5 is pivotally connected with 50 a bracket 13^a, on the cellar door, by a link 14. We preferably provide a slot in the end of arm 5 through which a pivot bolt 15 passes to permit bracket 13^a to be secured to the cellar door without any great degree 55 of accuracy.

When raising the door, link 10, which is pivoted to bracket 4, moves bell crank lever 7 which will move the door relatively to arm 5. This movement is permitted by the pivotal connection between arm 5 and brackets 11 and 13^a on the door. When the door is closed it will rest on cellar door support 3, the hinge construction being within the cellar opening, thus leaving no projecting parts on the outside of the door and 60 attaining a point which is very desirable when the cellar door is used on sidewalks. By constructing a hinge in this manner, a maximum cellar opening is obtained since the hinge can be readily secured to the side- 65 wall of the cellar opening.

While we have described our invention as taking a particular form, it will be understood that the various parts of our invention may be changed without departing 70 from the spirit thereof, and hence we do not limit ourselves to the precise construction set forth, but consider that we are at liberty to make such changes and alterations as fairly come within the scope of the 75 appended claims.

Having thus described our invention, what we claim as new and desire to secure by Letters Patent is:—

1. In combination with a door and a support; an arm hinged to the support and pivotally connected with the door by a link and a lever, and a link pivotally connecting the lever with the support. 85

2. In combination with a door and a support; an arm hinged to the support and pivotally connected with the door by a link and a bell crank lever, and means pivotally connecting the bell crank lever with the support. 90

3. In combination with a door and a support; an arm hinged to the support and pivotally connected with the door by a link and a bell crank lever, and a link pivotally connecting the bell crank lever with the support. 100

4. In combination with a door and a support; a bracket on the support; an arm hinged to the bracket and pivotally connected with the door by a link and a bell 105 crank lever, and a link pivotally connecting the bell crank lever with the bracket on the support.

5. In combination with a door and a support having a wall surrounding an opening; 110

2
a bracket secured to the wall; an arm hinged to the bracket and pivotally connected with the door by a link and a bell crank lever, and a link pivotally connecting the bell

5 crank lever with the bracket.

6. In combination with a door and a support; a bracket on the support; brackets on the door; an arm hinged to the bracket on the support and pivotally connected with
10 the brackets on the door by a link and a bell crank lever, and a link pivotally con-

necting the bell crank lever with the bracket on the support.
In testimony whereof we have signed our names to this specification in the presence of 15 two subscribing witnesses.

PAUL F. ELLMER.
CHARLES STREFF.
